Primary Examiner — Karen S Acker(57) **CLAIM**

The ornamental design for sandwich pick, as shown and described.

DESCRIPTION

The patent or application file contains at least one drawing executed in color. Copies of this patent or patent application publication with color drawing(s) will be provided by the Office upon request and payment of the necessary fee.

1. Sandwich pick

FIG. 1.1 is a front view of the sandwich pick;

FIG. 1.2 is a side view thereof; and

FIG. 1.3 is a top view thereof.

The sandwich pick is intended to be used for stacking and holding in place hot or cold food layers.

1 Claim, 3 Drawing Sheets
